FLEXIBLE SHAFT AND MOTOR CARRIER

**Willis D. Snyder and Wilbur J. Emmer,
Crestline, Ohio**

Application December 26, 1941, Serial No. 424,534

1 Claim. (Cl. 248—19)

This invention relates to a flexible shaft and motor carrier and has for an object to provide a simplified device of this character in which the weight of the device will be small, this being accomplished by the castored base sections being connected by the motor itself, thus eliminating the use of a separate base plate and its consequent weight.

A further object is to provide a device of this character having a special safety feature in the nature of a spring-pressed bearing for supporting the belt drive to the motor so that in the event accessories or tools become lodged in the work the spring will allow the belt to slip and relieve the strain on the flexible shaft and the accessory or tool.

A further object is to provide a device of this character having an arm provided with a loop through the medium of which the carrier may be suspended from a carriage mounted on an overhead track.

A further object is to provide a device of this character in which the rear base section is provided at opposite sides of the motor with supports or rests for receiving the flexible shaft when it is not in use without necessitating stopping of the motor.

A further object is to provide a device of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawings forming a part of this specification:

Figure 1 is a side elevation of a flexible shaft and motor carrier constructed in accordance with the invention.

Figure 2 is a top plan view of the carrier shown in Figure 1 with the motor removed.

Figure 3 is a rear elevation of the carrier.

Figure 4 is a front elevation of the carrier.

Figure 5 is a detail longitudinal sectional view showing the belt drive shaft, bearings therefor, post for the bearing and spring for yieldably supporting the post.

Figure 6 is a bottom plan view of the parts shown in Figure 5, removed from the standard.

Figure 7 is a front elevation of the parts shown in Figure 6 with the pulley guard in section.

Referring now to the drawings in which like characters of reference designate similar parts in the various views, the flexible shaft and motor carrier comprises a base including a front section 10 and a rear section 11, the front section being provided with a single castor 12 and the rear section being provided with a pair of castors 13. The front section is provided at its rear end with a transverse bar 14, as best shown in Figure 2, and the rear section consists of a transverse bar 15 having its end portions inclined outwardly and rearwardly. The castors 13 are connected to the angular end portions of the rear section 15. The base plate 16 of an electric motor 17 is secured respectively to the cross bar 14 and the rear section 15 of the base by bolts 18 and 19 so that the motor connects the two sections of the base together without the use of an additional base plate, thus promoting lightness in weight of the structure.

A standard 20 is carried by the front base section 10 and is provided at its upper end with a socket 21, best shown in Figure 5. The socket receives a post 22 which is provided at the top with a transverse head 23, best shown in Figure 7, and a cap plate 24 secured together by screws 25. The head is provided with a semi-cylindrical groove 26 to receive the lower side of a cylindrical housing 27 which is formed integral with the cap plate. The cylindrical housing extends longitudinally of the front base section 10, as best shown in Figure 1, and at the outer end is provided with stepped threaded shoulders 28 and 29 to receive the outer casing 30 of a flexible shaft 31, the core of which is to be driven by the motor 17.

of which is to be driven by the motor ... A counter shaft 32 is engaged longitudinally through the housing 27 and terminates at the front end near the stepped threaded shoulders where it is provided with a substantially rectangular socket 33 for receiving the core of the flexible shaft 31. A pair of spaced collars 34 are secured in spaced relation on the shaft by set screws 35 and confine ball bearing assemblies 36 against the ends of the housing to support the shaft for anti-friction rotation in the housing. A packing washer 37 is interposed between the rear ball bearing assembly and the rear end 38 of the housing, this end preferably being in the nature of a flanged cap screw-threadedly engaged with the rear end of the housing, as best shown in Figure 5.

The rear end of the shaft projects through the rear end 18 of the housing and is equipped with a pulley 39 which is provided with a plurality of

circumferential grooves 40 of different diameters in a radial direction to interchangeably receive a belt 41 which is trained over a similar pulley 42 on the shaft 43 of the electric motor 17, as best shown in Figure 1.

The post 22 is supported upon a helical spring 44 which is confined in the socket 21 of the standard 20, as best shown in Figure 5. The spring yieldably supports the shaft 32, which carries the flexible shaft 31. Should accessories or a tool become lodged in the work, the spring will yield and allow the belt 41 to slip, thus relieving strain on the flexible shaft and on the tool or accessory.

A one piece substantially convex cap 45 is disposed over the pulley 39 and is provided with securing lugs 46, best shown in Figure 7, with which the beforementioned screws 35 are threadedly engaged to secure the cap 45 to the cap plate 24 of the head 23 carried by the post 22.

As best shown in Figures 1 and 2, an arcuate arm 47 extends rearwardly from the standard 20, above the motor 17 and forms a handle through the medium of which the device may be manipulated if desired. The arm is equipped at the end with a loop 48, through the medium of which the device may be suspended from the carriage of an overhead track when desired.

Upwardly extending bifurcated arms 49 are secured by the motor securing bolts 19 to the transverse bar 15 of the rear base plate 16. The upper ends of the arms are adapted to receive and support the free end of the flexible shaft 31 when the shaft is not in use, as best shown in Figure 1.

From the above description it is thought that the construction and operation of the invention 10 will be fully understood without further explanation.

What is claimed is:

15 In a support for a portable power plant of the type having a motor and a countershaft driven from the motor; an integral frame section comprising a longitudinally extending elongated bottom portion having its rear end rigidly fastened to the motor, a standard rising vertically from the front part of said longitudinally extending portion, said standard having a socket in its upper end adapted to receive a depending projection of a countershaft support, and a guiding and lifting arm extending rearwardly from the upper part of the standard.

WILLIS D. SNYDER.
